Primary Examiner — Ryan Harvey(74) *Attorney, Agent, or Firm* — Cameron LLP**CLAIM**

The ornamental design for a double handle with clasp for exercise equipment, as shown and described.

DESCRIPTION

FIG. 1 is a right front perspective view of the double handle with clasp for exercise equipment of the present invention; FIG. 2 is a front view of the double handle with clasp for exercise equipment of FIG. 1;

FIG. 3 is a rear view of the double handle with clasp for exercise equipment of FIG. 1;

FIG. 4 is a left side view of the double handle with clasp for exercise equipment of FIG. 1;

FIG. 5 is a right side view of the double handle with clasp for exercise equipment of FIG. 1;

FIG. 6 is a top view of the double handle with clasp for exercise equipment of FIG. 1; and,

FIG. 7 is a bottom view of the double handle with clasp for exercise equipment of FIG. 1.

The broken lines shown in FIGS. 1-5 illustrate stitching which forms part of the claimed design.
